UNITED STATES PATENT OFFICE.

HARRY C. JONES, OF LARCHMONT, NEW YORK, ASSIGNOR TO LITHOPRINTEX CORPORATION, OF NEW YORK, N. Y., A CORPORATION OF NEW YORK.

COUNTERING HEAD.

Application filed February 21, 1924. Serial No. 894,194.

To all whom it may concern:

Be it known that I, HARRY C. JONES, a citizen of the United States, and resident of Larchmont, in the county of Westchester and State of New York, have invented certain new and useful Improvements in Counting Heads, of which the following is a specification.

My invention relates to counting heads, and more particularly to counting heads for counting revolutions and fractions of a revolution of an operating shaft and for arresting the shaft from further movement after it has been rotated a given number of revolutions.

My invention is adapted to be used with a variety of machines in which some operating part is to be arrested from further movement after it has moved through a predetermined distance or moved through a predetermined number of cycles of operation as the case may be.

More particularly it is adapted to be used with machines in which the predetermined movement of one part must be held within narrow limits, such as, for example, photo-compassing machines, step-and-repeat machines, lathes, milling machines, etc., but in the form herein illustrated the invention is especially useful for, and is intended to be used in connection with, what is known as a photo-compassing machine such as shown and described in my co-pending application Serial No. 699,167, filed March 14, 1924, in which machine a negative is provided which must be moved between exposures with great accuracy in front of sensitized surface so as to properly position upon said surface prints of objects or designs to be photographed from the negative onto the sensitized surface.

One of the objects of my invention is to provide an efficient and durable counting head by means of which after an operating shaft has been rotated a given number of revolutions it will be positively arrested from further operation, and the counting mechanism may be reset to again arrest the shaft after it has been moved through the same number of revolutions, and so on.

Another object of the invention is to pro-

vide a counting head by means of which a predetermined number of complete revolutions and fractions of a revolution of the shaft may be permitted and then the shaft positively arrested from further operation, and in which the parts may be readily reset for a duplicate counting operation.

Still another object of the invention is to provide means when motive power is used for driving the shaft the motive power may automatically be cut off a short interval before the positive arresting operation takes place.

The invention consists in the novel features and combination of parts which are hereinafter shown and described in their preferred form, and the invention is more particularly pointed out in the appended claims.

Further objects and advantages of the invention will more fully appear from the following description taken in connection with the accompanying drawings, illustrating by way of example the preferred embodiment of the invention, and in which—

Fig. 1 is a front elevation.

Fig. 2 is a section on line 2—2 of Fig. 1.

Fig. 3 is a sectional view showing details of the cam locking ring.

Fig. 4 is a sectional view looking from the rear and showing the details of the riders.

Fig. 5 is a sectional view showing details of a cut out switch.

Fig. 6 is a view showing details of a cut out switch and locking means.

Fig. 7 is another view showing the same details as Fig. 6.

Fig. 8 is a diagrammatic sketch showing the electric circuit of a motive means for driving the shaft.

Fig. 9 shows a modification of Fig. 5; and

Fig. 10 shows a modification of Fig. 9.

Referring to the drawings (Figs. 1 and 2), 1 is the shaft whose rotation is to be arrested after a predetermined number of revolutions or/and a fraction of a revolution has been completed. Suitable motive means such as an electric motor 2 is provided for driving the shaft through any suitable gear train such as a spur gear 3

2
keyed to the shaft of the motor, an idle gear 4 keyed to hub 5 slidably mounted on axle 5, and driven spur gear 6 secured to shaft 1. The sliding gear 4 acts as a means of disconnecting the motive means from the shaft 1 and is adapted to be held either in or out of mesh with gears 3 and 6. The shaft 1 is supported at its outer end by a plate 7 bolted to any suitable part of the machine such as at 8, and the shaft is preferably directly supported by antifriction means such as ball race bearing 9 which is mounted in a recess in plate 7.

A sleeve 10 (Fig. 2) carrying a flange 11 bearing teeth or serrations 11' is secured to shaft 1 by suitable means such as a key 12. A spur gear 14, in this instance having 101 teeth, and formed on a hub 13, is mounted on sleeve 10 free to rotate with respect thereto. A spur gear 15 having one or more teeth less than gear 14, or in this instance 100 teeth, and formed on a hub 16, is mounted on hub 13 free to rotate with respect thereto. An idle gear 17 (Fig. 1), is mounted on a stationary member such as plate 7 and meshes with gears 14 and 15. An index member 18, for indicating complete revolutions, and preferably in the general form of a disc, is mounted on hub 16 to rotate with respect thereto and is held on hub 16, which in turn is held on hub 13 by a second index member 19 for indicating fractions of a revolution shown in the general form of a disc, which is attached to hub 13 as by screws 20. A crank handle 21 is secured to sleeve 10 by screws 22 and forms together with sleeve 10 and flange 11 constraining means for restricting the axial movement of gears 14 and 15 and index members 18 and 19 and the entire unit thus formed is held on shaft 1 by a washer 23 together with its cooperating nut 24 which is locked in position by a set screw 25. A grease cup 26 is screwed into a counterbore 27 in shaft 1 and supplies lubricant to the several moving parts through lubricating holes 28 and cooperating lubricating holes in the hubs of the gears as at 28' and 28" in the usual manner.

50 *Index members.*

A shell or casing 29, in the general form of a drum, is secured to plate 7 by suitable means such as screws 30 and forms a partial enclosure for the moving parts. The face of this drum carries index marks forming a dial 31 which will be referred to as the immovable or stationary index. Surrounding the periphery of this dial are serrations 31' equal in number to the marks on the dial which in this case are 100 in number, although any suitable number of divisions may be employed.

The index member 18 for complete revolutions carries index marks forming a dial 32

adjacent its peripheral front face. A ring 33 is attached to the rear face of index member 18 adjacent its periphery and inside teeth or serrations 34 are formed therein for a purpose to be hereinafter described. These 70 are equal in number to the division on dial 32 which are equal in number to the teeth of gear 15 which in this case are 100 in number. Index plate 19 for fractions is provided with a series of perforations 35 75 formed concentric to shaft 1 and equal in number to the divisions on dial 31 (in this instance 100). Registration means such as recesses 36 and 36' are formed in peripheral portions of index members 18 and 19 at 80 points corresponding to the zero position of dial 31, the function of which will be more fully pointed out hereinafter.

85 *Locking means and stops.*

A locking lever 37 (Fig. 1) pivoted at 38 to a fixed lug 39 herein shown as a part of drum 29 carries a tongue 40 (see also Figs. 2 and 4) adapted to enter notches or recesses 36—36' when in register, and thereby lock index members 18 and 19 against rotation for purposes to be more fully described later. Fitted in the recess in the end of locking lever 37 (Fig. 4) is a vanishing stop member 41 normally held in a 95 raised position by a spring 42 and adapted to be pressed downward by a push pin 43.

A rider 44 is slidably mounted on the periphery of index member 18 and carries a tongue 45 adapted to engage the serration 100 34 in ring 33. The tongue being normally held locked in one of said serrations on a portion of ring 33 by spring 46 and adapted to be released for adjustment by means of push button 47. The face of the rider is adapted to abut against the vanishing stop 41 when the latter is in its exposed or operative position for setting the index number 18 for complete revolutions, as described following.

A rider 48 is slidably mounted on the peripheral flange bearing the dial 31 and carries a tongue 49 adapted to engage one of the serrations 31' on the periphery of the drum 29; the tongue being normally held locked in one of said serrations by spring 50 and adapted to be released for adjustment by means of push button 51. A vanishing stop 52 is slidably fitted in rider 48 with a spring 53 normally holding it in an inoperative position and adapted to be pressed into an operative position by push pin 54. These vanishing stops are employed so that normally i. e. when not in actual use, they are retracted and do not form an obstruction to the relative movement of the parts to which they are respectively attached.

A fixed stop 55 is attached to index member 19 and adapted to abut against vanish-

ing stop 52 when the latter is in an operative or exposed position, for setting the index member 19 for fractional revolutions, to be more fully described later.

- 6 Crank handle 21 is provided at one end with a handle 56 and at its opposite end with a plunger pin 57 adapted normally to be pressed into one of the perforations 35 in the index member 19 by spring 58. When, 10 however, it is desired to release the crank handle from the index member 19 this is accomplished by lifting up the knurled head 59 of the pin 57 and turning the knurled head until pin 60 rests on boss 61.
- 15 Means for locking gear 15 to index member 18 is accomplished as follows: Referring to Figs. 2 and 3, an annular flange 62 projects from the rear of index member 18, in such a position that it lies contiguous to 20 a serrated portion 63 formed on gear 15. A suitable locking device such as a locking plunger 64 is slidably mounted in a slot 64' in the annular flange 62 and is normally held out of engagement with the serrations 25 63 by a spring 65, one end of which is fixed in flange 62 and the other end of which carries the plunger 64 and is free to move in slot 65'. A plunger actuating member such as cam ring 66 is mounted on flange 62 30 and held in position, free to be oscillated within certain limits, by set screws 67 screwed into the flange with their free portions engaging slots 68 in cam ring 66. A cam surface 69 engages the plunger 64 so 35 that when the cam ring is moved counter-clockwise, as illustrated by the arrow in Fig. 3, the locking plunger 64 will be pressed into one of the serrations 63 to thereby lock gear 15 to index member 18. Projections 40 70 are formed at intervals around the periphery of cam ring 66 and provide means for readily catching hold of the cam ring to move the same. One of these projections is therefore always in a position to be readily accessible from the same point, no matter in what position of rotation the plunger 64 is in, since ring 66 surrounds the shaft 1. A spring pressed plunger 71 mounted on flange 62 engages a recess 72 in cam ring 66 45 to normally hold the cam ring in such position that locking pin 64 will be held in engagement with one of the serrations 63 and thereby the gear 15 and index member 18 50 held locked together. However, when the cam ring is rotated counter-clockwise the plunger 71 is forced down compressing the spring and the point of the plunger rides on the inner side of the cam ring.

55 A means for locking the shaft 1 against rotation while the index members are being set is shown in Figs. 6 and 7. A bolt 73 is mounted to slide radially on plate 7 and adapted to be moved by a knurled handle 74 slidably in a slot 75 in plate 7. The end 60 of the bolt as at 76 is adapted to engage the

serrated periphery 11' of flange 11 and thereby lock this flange and its hub 10, together with shaft 1 attached thereto, against rotation.

Setting.

70

75 Before describing the actual setting, a brief statement of some important facts, and a résumé of some already stated above, will be made.

Gear 14 has 101 teeth, gear 15 has 100 teeth, and the idle gear 17 is in mesh with both of these gears. Therefore each time gear 14 makes one revolution gear 15 makes one revolution plus one tooth. Then with 80 fraction index member 19 secured to gear 14, if we lock index member 18 to gear 15, and connect gear 14 to shaft 1, each time shaft 1 makes one revolution index member 18 will have gained 1 tooth distance relative 85 to index member 19. Or stated another way, for each tooth distance gained by the index member 18 relative to index member 19 the shaft 1 will have made one revolution. Also, the index members 18 and 19 when attached 90 respectively to gears 15 and 14, which are in mesh with idle gear 17, are connected together through the gears 15, 14 and 17 in the ratio of 100 to 101, the gears acting as 95 a differential: Hence when the gear 14 together with the index member 19 is rotated a given angular distance gear 15 and index member 18 are rotated the same angular distance plus 1/100 revolution. Therefore to rotate index member 19 1/10 revolution 100 the index member 18 has been rotated 1/10 plus 1/100 or, as measured on gear 15, 10 teeth plus 1/10 tooth.

Setting counting head.

105

Assuming, as an example, that it is desired to set the counting head for 15 and 1/10 revolutions of the shaft 1, which might be a lead screw, a jack-screw or a driving or driven shaft, and which for 110 brevity will be referred to hereinafter as a shaft. The shaft is locked by moving the bolt 73 into engagement with flange 11 as described above. Then the push pin 47 is 115 pressed in and rider 44 is now moved clockwise (Fig. 1) and set on division 15 of dial 32 on index member 18, pin 47 is released and tongue 45 (see also Fig. 4) engages the corresponding serration on ring 33 and holds the rider in this position. Lever 37 is 120 swung upward about its pivot 38 until tongue 40 is out of engagement with recesses 36-36' and rides in the periphery of index member 18 and 19 as 18 is rotated as 125 described following. Pin 43 on the lever arm 37 is now pushed down lowering the vanishing stop 41 which is held in this position and index member 18 is rotated counter-clockwise until the face of the rider 44 abuts vanishing stop 41. This has moved 130

index member 18 back of fraction index member 19 an angular distance equal to 15 teeth of gear 15, since ring 33 has 100 serrations and gear 15 has 100 teeth. Next lock index member 18 to gear 15 by turning cam ring 66 (Figs. 2 and 3). This has set the counting head for 15 complete revolutions.

This locks index members 18 and 19 together, through the differential composed of 10 gears 14, 15, and 17, in a ratio of 100 to 101. Next move rider 48 counter-clockwise to division 10 by pushing in pin 51 which releases it and then sliding along and releasing pin 51 to cause 15 tongue 49 to engage one of the serrations 31' corresponding to 10 on the dial 31 of the immovable index member 29. Then unlock crank 21 from index member 19 by pulling out knurled head 59, thus disengaging pin 20 57 from the perforation 35, and rotate the knurled head to lock pin 57 in an inoperative position.

Push in pin 54 on rider 48, mounted on dial 31, (Figs. 2 and 3) thus bringing the vanishing stop 52 into operative position and rotate index member 19 counter-clockwise until the fixed stop 55 abuts against the vanishing stop 52 carried by rider 48. This last movement has moved index member 19 an angular distance equal to 10 teeth and index member 18 an angular distance equal to 10 teeth plus 1/10 tooth. Therefore index member 18 has been set counter-clockwise with respect to index member 19 a total peripheral distance equal to 15 and 1/10 teeth, and hence the registration recesses 36-36' have been separated this distance.

As explained above the shaft will have 40 to rotate clockwise 15 and 1/10 revolutions before these registration recesses come into proper register again. Lock crank 21 to index member 19 by means of pin 57 engaging the corresponding perforation 35, and unlock shaft 1 by pulling out bolt lock 73. 45 Shaft 1 is now ready to be rotated by suitable means either by motive power represented by motor 2 or by manual means which may be applied by means of handle 56 on crank 21.

50

Repeat setting.

The repeat setting of the counting head after an operation has taken place will now be described. First lock shaft 1 against 55 rotation as before, by plunger 73, unlock cam ring 66 thereby releasing index member 18 from its gear 15. Move index member 18 until rider 44 (already set from previous operation) engages vanishing stop 41. 60 Then lock gear 15 and index member 18 by means of cam ring 66; unlock crank handle 21, rotate both dials backwards or counter-clockwise until stop 55 abuts vanishing stop 52 on rider 48 which has remained set from 65 the previous operation as before described;

release crank pin to lock crank 21 to index member 19 as before; unlock shaft 1 by releasing bolt 73 from engagement with flange 11, and the setting has been repeated and the shaft is now ready to be rotated.

70

Manual operation and automatic stop.

When manual operation is employed any suitable means may be used. In the embodiment shown herein handle 56 on crank 21 is rotated and pin 57 on the opposite end of crank 21 drives index member 19 which is fastened to hub 13, keyed to shaft 1, gear 14 is an integral part of hub 13 and is in mesh with idler 17 (Fig. 1) which is also 80 in mesh with gear 15, which is locked to index member 18. So that as shaft 1 is rotated index member 18 gains 1 tooth relative to index member 19 at each revolution, and after 15 and 1/10 revolutions have 85 been made by shaft 1 and index member 19, index member 18 has regained the 15 and 1/10 tooth peripheral distance and the recesses 36-36' in index members 18 and 19 respectively have come into register, 90 whereat tongue 40 on the end of lever 37 drops into register (pulled down by spring 38') and locks shaft 1 against further rotation.

95

Electric switches.

When motive operating means is desired it is advisable to have means for cutting off the motive power so that too great a shock will not occur when the tongue 40 falls into recesses 36-36'. It is also preferable to have certain safety cut-out switches and master switches to make the motive means inoperative when the index members are being set for a certain position. Likewise 105 when it is desired to use the motive means without the counting head it is desirable to provide a means to prevent these cut-out switches from functioning. These various switches for controlling the motive means 110 will now be described.

Bolt 73 is provided with a slotted portion 77 for engagement with the lever 78 of an electric switch 79 which is attached to plate 7; so that when the bolt 73 is moved forward to lock the shaft 1 from rotating the lever 78 is moved forward to operate the switch to close a relay switch to be described and for purposes to be set forth hereinafter. This switch will be referred to as switch A. 120

A switch 79' (Fig. 1) is mounted adjacent the forked end of lever 37 so that when lever 37 is raised and thrown back beyond its normal position the upper forked end of lever 37 will engage the lever 78' to close 125 the circuit in which it is placed for purposes to be hereinafter described. A spring 38' is so positioned that it acts as a toggle spring to hold lever 37 in either of the extreme 130 positions to which it might be moved. Now-

ever when the lever 37 is held in a neutral position by tongue 40 riding upon the periphery of index members 18 and 19, or when tongue 40 is in recesses 36-36', lever 78' is in a neutral position and switch 79' is opened. This switch will be referred to as switch B.

Referring to Figs. 1, 2, and 5 (more particularly Fig. 5) a support 80 is secured to index member 19, and pivotally mounted thereon and spring pressed outwardly by spring 81 a roller 82 is pivoted on a radially extending axis 83 so that the roller 82 describes a concentric path on the face of index member 18 during the relative movement of index members 18 and 19. A slot with beveled ends is cut through index member 18 in the path of roller 82 and sufficiently wide to permit roller 82 to pass therethrough and contact with a plate 85 carried by an insulated base 86 attached to a non-rotatable part of the counting head such as plate 7. Roller 82 and slot 84 are so positioned on index members 18 and 19 relative to each other that they coincide at a certain peripheral tooth distance ahead of that point at which recesses 36-36' come into register. Or in other words roller 82 contacts plate 85 a certain number of revolutions (in this instance two) ahead of the time when recesses 36-36' come into register. Now if this roller 82 and plate 85 be placed in a circuit; by connecting one side of the circuit to roller 82 through index member 19 and a part of its supporting structure, and plate 85 to the other side of the circuit, then at a time 2 revolutions before recesses 36-36' of index members 18 and 19 respectively come into register this circuit will be closed to operate a relay switch, to be described, to cut out the motor as set forth hereinafter. This switch will be referred to as switch C.

Notice operation.

In the embodiment shown (Fig. 2) an electric motor 2 is shown. So the motive means will be described in connection with this embodiment, it being understood that any other suitable motive means may be employed. Likewise where the relay switches above referred to, and to be described hereinafter, are shown as operating to break the electric circuit furnishing power to the motor 2, they may also be adapted to cut out or make inoperative any other motive means which it may be found desirable to employ, all of which will be well understood by those skilled in the art, after fully understanding this embodiment of my invention.

Referring to Fig. 8 wherein the various parts are diagrammatically represented, the motor is shown at 2, the power circuit 55 for supplying electrical energy to the motor

is represented as 87, and 88 represents a circuit breaker switch to be positively operated to start or stop the motor and of the type well known in the art where an interruption of electrical energy in circuit 87 will throw out switch 88 to break the circuit until switch 88 is again thrown in and the circuit 87 otherwise closed. Relay switches 89, 89' and 89'' are interposed in the circuit and are supplied with electrical energy by any suitable source such as a storage battery 90, of low voltage (about 10 volts being used). The relay switch 89' is in parallel to or shunted around switch 89''.

These relays are arranged with means to normally hold the circuit open, such as springs 91, 91' and 91'' and the relays are magnetized to oppose this action and thereby hold the circuit closed in so far as their operation is concerned. It will therefore be seen that even with the switch 88 closed, if the electrical energy of either of the relay circuits 89, or 89' is cut off, the circuit breaker 88 will operate to keep the circuit open and the electrical energy cut off, thereby cutting off, or keeping shut off, the motor 2 until switch 88 is positively closed again. If however the relay circuit 89' is closed the relay circuit 89'' is thereby made ineffective and while switches A and B are closed the switch 88 will be the operating switch. Switches A, B, and C, above referred to are inserted in the respective circuits of relays 89, 89' and 89''. It will therefore be understood that if either of the switches A or C are operated as above described to cut off the electrical energy from their respective circuits the associated spring will open the corresponding relay switch and either cause the motor to be cut off or else prevent its being turned on, as the case may be; with this exception, that if switch B is operated to close relay 89' the switch C will be ineffective to cut out the motor 2.

Now then, referring to Figs. 1, 6, and 8, as the bolt 73 is moved forward to lock the shaft 1 against rotation the switch A breaks the circuit of the corresponding relay 89 and causes the circuit 87 to be opened thereby preventing the motor from starting so long as shaft 1 is locked and also preventing the switch 88 from being operatively closed. However as the counting head is set and during which procedure lever 37 is raised to neutral position, and switch A closed as bolt 73 is withdrawn, the circuit is now closed in so far as the relay switches are concerned. At this time switch C is inoperative with roller 82 riding on the face of index member 18. Now switch 87 is closed, the motor cuts in and the shaft 1 is rotated. Assuming the same setting described above namely for 15 1/10 revolutions, after the shaft 1 has rotated 13 1/10 revolutions the roller 82 comes opposite slot 120

84 and is pressed against plate 85 by spring 81 thereby closing the contact across the circuit to relay 89" and short-circuiting and causing the magnet of the same to become inoperative and hence open the circuit 87 and cut out the motor. Then the handle 56 on the crank 21 is turned manually the remaining revolutions to bring recesses 36 and 36' into register. The slot 84 is sufficiently long for the relative movement of the roller 82 to take place in the slot so as not to bring the roller on the face of index member 19. Therefore at the completion of the two final revolutions the contact is again made and this prevents the motor circuit 87 from being closed until a new setting of the index members has been made, thereby breaking the contact between roller 82 and plate 85. Tongue 40 now falls into recesses 36-36' and the shaft is locked against further rotation.

To make it possible to operate motor 2 independently of the counting head a shunt switch is embodied in switch B which functions as follows. By picking up lever 37 and moving it clockwise to its farthest position switch B is closed thereby shunting around switch 89" and by closing switch 88 the circuit 87 will be closed so that even if switch C is operated by the dial, and the relay 89" thereby opened, the motor circuit 87 will remain closed through the shunt circuit completed by the closing of relay 89'.

The control of circuit 89" made by switch C may be accomplished in several ways, of which switch C is the preferred form. Two other means of operating this circuit both of which I have employed in connection with my counting heads are shown in Figs. 9 and 10.

Referring to Fig. 9, segments of index members 18 and 19 are diagrammatically represented and the notches or recesses 36-36' are shown approaching alignment. Three more revolutions will bring them into register. At the position shown, however, the notches 92 and 93 come into register and allow the bar 94 to drop down carrying therewith the contact to open relay circuit 89" and thereby open circuit 87 (Fig. 8).

Instead of the notches 92-93 however, insulated blocks 92'-93' (Fig. 10) may be inserted in the index members placed in the circuit; bar 8 acting as the electrical connection.

As the insulated blocks come into register the circuit is broken and relay circuit 89" opened and the motive means cut off as hereinbefore described.

Having thus described my invention with particularity with reference to the preferred embodiment of the same and having referred to some of the modifications thereof, it will be obvious to those skilled in the art, after

understanding my invention, that other changes and modifications may be made therein without departing from the spirit and scope of my invention, and I aim in the appended claims to cover such changes and modifications as are within the scope of my invention.

What I claim is:

1. In a counting head, the combination of a shaft the rotations of which are to be counted, a pair of differential gears geared together, a first index member for indicating fractional revolutions connected to one of said differential gears and adapted therewith to rotate relative to the shaft, a second index member for indicating complete revolutions free to rotate with respect to said shaft and the other of said differential gears, and means for selectively locking said second index member to the other differential gear, whereby with said first index member connected to its gear and when said second index member is locked to its gear, and said second index member is rotated, the two index members are caused to be moved angularly one with respect to the other for the fractional setting of the index members.

2. In a counting head, the combination of a shaft the rotations of which are to be counted, a pair of differential gears geared together, a first index member for indicating fractional revolutions connected to one of said differential gears and adapted therewith to rotate relative to the shaft, a second index member for indicating complete revolutions free to rotate with respect to said shaft and the other of said differential gears, means for selectively locking said second index member to the other differential gear, whereby with said first index member connected to its gear and when said second index member is locked to its gear, and said second index member is rotated, the two index members are caused to be moved angularly one with respect to the other for the fractional setting of the index members, means connecting one of said index members to the shaft whereby when the shaft is rotated said index members are driven, and locking means adapted to engage registering portions on the two index members to stop the rotation of the shaft when through the rotation of the shaft said portions are brought into alignment.

3. In a counting head, the combination of a shaft the rotations of which are to be counted, a pair of differential gears geared together, a first index member for indicating fractional revolutions connected to one of said differential gears and adapted therewith to rotate relative to the shaft, a second index member for indicating complete revolutions free to rotate with respect to said shaft and the other of said differential gears, means for selectively locking said second

index member to the other differential gear, whereby with said first index member connected to its gear and when said second index member is locked to its gear, and said second

locking said index member and gear together comprising a locking member and an actuating member extending around said shaft.

5 index member is rotated, the two index members are caused to be moved angularly one with respect to the other for the fractional setting of the index members, means connecting said first index member to the shaft 70 whereby when the shaft is rotated said index members are driven, and locking means adapted to engage registering portions on the two index members to stop the rotation of the lead screw when through the rotation 75 of the shaft said portions are brought into alignment.

7. In a counting head, the combination of a shaft to be rotated, an index member, a gear associated therewith, and means for locking said index member and gear together comprising a locking member, and an actuating member extending around said shaft 80 and adapted when rotated with respect to said shaft to cause said index member and said gear to be locked together.

8. In a counting head, the combination of an index member, a gear adapted to be attached thereto in fixed rotative position therewith, a plunger carried by said index member and adapted to engage a portion of said gear, and an actuating member for pressing said plunger into engagement with said gear whereby said index member and said gear may be locked together. 85
9. In a counting head, the combination of an index member, a gear adapted to be attached thereto in fixed rotative position 90 therewith, a plunger carried by said index member and adapted to engage a portion of said gear, an actuating member for pressing said plunger into engagement with said gear whereby said index member and said gear may be locked together, and means for normally frictionally holding said actuating member in operative position to lock said index member and said gear together. 95
10. In a counting head, the combination of 100 movable and fixed index members, a shaft to be rotated and means for setting said index members relative to each other for governing the rotation of said shaft, said means including fixed and movable stops for limiting the relative movements of said index members, said stops being adapted for engagement with each other for setting said index members but free to pass each other unobstructed during the rotation of said shaft.

105 11. In a counting head, the combination of a shaft to be rotated, a first index member and a second index member, said members having divisions adapted respectively to indicate fractional and complete revolutions of said shaft, means for relatively setting said index members to govern the complete revolutions, differential means including a gear associated with each of said index members for relatively setting said index members to govern the fractional revolutions before said shaft is rotated, and means for rotating said shaft the fractional and complete revolutions after said index members have been set for governing fractional and complete revolutions. 115
120 12. In a counting head, the combination of a shaft to be rotated, an index member, a gear associated therewith, and means for finishing the final complete revolutions. 125

65 6. In a counting head, the combination of a shaft to be rotated, an index member, a gear associated therewith, and means for

120

of a shaft to be rotated, a first index member and a second index member, said members having divisions adapted respectively to indicate fractional and complete revolutions of said shaft, means for relatively setting said index members to govern the complete revolutions, differential means including a gear associated with each of said index members for relatively setting said index members to govern the fractional revolutions before said shaft is rotated, motive means for rotating said shaft a part of the complete rotative movement desired after said index members have been set for governing fractional and complete revolutions, and manual means for completing the final rotative movement desired.

13. In a counting head, the combination of a shaft to be rotated, a first index member and a second index member, said members having divisions adapted respectively to indicate fractional and complete revolutions of said shaft means for relatively setting said index members to govern the complete revolutions, differential means including a gear associated with each of said index members for relatively setting said index members to govern the fractional revolutions before said shaft is rotated, motive means to rotate said shaft, cut out means cooperating with said motive means to cut out said motive means before the total rotative movement allowed by the setting of said index members has been completed, and means to manually complete said total rotative movement.

14. In a counting head, the combination of a shaft to be rotated, a first index member and a second index member, said members having divisions adapted respectively to indicate fractional and complete revolutions of said shaft, means for relatively setting said index members to govern the complete revolutions, differential means including a gear associated with each of said index members for relatively setting said index members to govern the fractional revolutions before said shaft is rotated, motive means to

rotate said shaft, cut out means cooperating with said motive means to cut out said motive means before the total rotative movement allowed by the setting of said index members has been completed, and auxiliary cut out means to cause said first cut out means to become ineffective.

15. In an index device, a substantially drum shaped fixed member, carrying index marks on its face, a rider movable along said index marks, a vanishing stop on said rider, a shaft mounted for rotation in said member, a sleeve on said shaft rotatively connected therewith, means for locking said shaft against rotation, a crank connected to said shaft for rotating said shaft, a first spur gear mounted on said sleeve free to rotate thereon, a dial secured to the hub of said spur gear, a stop on said dial, a second gear mounted on the hub of said spur gear free to rotate thereon, a second dial mounted on the hub of said second spur gear free to rotate thereon, means for locking said second gear to said second dial, a rider on said second dial, a vanishing stop on said rider, a catch pivotally mounted on said drum shaped member, a vanishing stop on said catch, and an idle spur gear in mesh with said first and second spur gears.

16. In an index device, a substantially drum shaped fixed member, a shaft mounted for rotation in said member, a sleeve on said shaft rotatively connected therewith, a crank connected to said shaft for rotating said shaft, a first spur gear mounted on said sleeve free to rotate thereon, a dial secured to the hub of said spur gear, a second gear mounted on the hub of said spur gear free to rotate thereon, a second dial mounted on the hub of said second spur gear free to rotate thereon, means for locking said second gear to said second dial, and an idle spur gear in mesh with said first and second spur gears.

In testimony whereof I have signed my name to this specification.

HARRY C. JONES.
